UNITED STATES PATENT OFFICE.

HENRY BERGER, OF NEW YORK, N. Y.

DESIGN FOR OBLONG CENTER-PIECE.

Specification forming part of Design No. 5,211, dated August 22, 1871.

To all whom it may concern:

Be it known that I, HENRY BERGER, of the city, county, and State of New York, have invented a new and original Design for Oblong Center-Piece; and I do hereby declare the following to be a full, clear, and exact description thereof, which will enable those skilled in the art to make and use the same, reference being had to the accompanying drawing forming part of this specification, which drawing represents a plan of this design.

The distinguishing feature of this design is an oblong rim with broken corners and triangular pointed ends. The long sides of the oblong rim bulge out in the center and are covered by a wreath of foliage which extends over the space inclosed by said rim. In the center of the oblong rim is situated a button ornamented by arabesques and surrounded by ornaments composed principally of grecs and squares with depressed sides.

In the drawing, A designates a center-piece provided with an oblong rim, B, the corners *a* of which are broken and partly covered by

leaves *b*. The ends *c* of the rim are triangular and ornamented by arabesques. The long sides of the oblong rim B bulge outward, forming segments *d*, which are partly covered by a wreath, *e*, which extends over a portion of the space inclosed by the rim B. In the center of the rim B is a button, C, ornamented by arabesques and surrounded by ornaments composed principally of grecs *f* and squares *g* with depressed sides.

What I claim as new, and desire to secure by Letters Patent, is—

1. In a center-piece, the oblong rim B with broken corners, triangular ends, and segmental sides, as shown and described.
2. The wreath *e*, in combination with the oblong rim B, as shown and described.
3. The ornaments *f* *g* surrounding the central button C, as shown and described.

This specification signed by me this 8th day of July, 1871.

HENRY BERGER.
